CLAIM

The ornamental design for a high energy laser defense weapon system as shown and described.

DESCRIPTION

FIG. 1 is a front perspective view of a high energy laser defense weapon system showing the unique design;

FIG. 2 is a right side view thereof;

FIG. 3 is a front elevation view thereof;

FIG. 4 is a left side view thereof;

FIG. 5 is a back elevation view thereof;

FIG. 6 is a front perspective view of another embodiment of the high energy laser defense weapon system showing the unique design;

FIG. 7 is a right side view thereof;

FIG. 8 is a front elevation view thereof;

FIG. 9 is a left side view thereof; and,

FIG. 10 is a back elevation view thereof.

FIGS. 6-10 of the drawings are shown with broken lines to indicate portions thereof and environmental structure of the high energy laser defense weapon system that form no part of the claimed design.
